(57) **CLAIM**

The ornamental design for a multi-camera mobile device, as shown and described.

DESCRIPTION

FIG. 1 is a front view of a multi-camera mobile device, showing our new design, in accordance with a first embodiment.

FIG. 2 is a rear view thereof, in accordance with the first embodiment.

FIG. 3 is a right side view thereof, in accordance with the first embodiment.

FIG. 4 is a left side view thereof, in accordance with the first embodiment.

FIG. 5 is a top view thereof, in accordance with the first embodiment.

FIG. 6 is a bottom view thereof, in accordance with the first embodiment.

FIG. 7 is a top-left-front perspective view thereof, in accordance with the first embodiment.

FIG. 8 is a bottom-right-front perspective view thereof, in accordance with the first embodiment.

FIG. 9 is a bottom-right-rear perspective view thereof, in accordance with the first embodiment.

FIG. 10 is a top-left-rear perspective view thereof, in accordance with the first embodiment.

FIG. 11 is a front view of a multi-camera mobile device, showing our new design, in accordance with a second embodiment.

FIG. 12 is a rear view thereof, in accordance with the second embodiment.

FIG. 13 is a right side view thereof, in accordance with the second embodiment.

FIG. 14 is a left side view thereof, in accordance with the second embodiment.

FIG. 15 is a top view thereof, in accordance with the second embodiment.

FIG. 16 is a bottom view thereof, in accordance with the second embodiment.

FIG. 17 is a top-left-front perspective view thereof, in accordance with the second embodiment.

FIG. 18 is a bottom-right-front perspective view thereof, in accordance with the second embodiment.

(Continued)

FIG. 19 is a bottom-right-rear perspective view thereof, in accordance with the second embodiment; and, FIG. 20 is a top-left-rear perspective view thereof, in accordance with the second embodiment. The broken lines are directed to environment and are for illustrative purposes only. The broken lines form no part of the claimed design. The “360° intel” logo in FIGS. 2, 9, and 10 of the first embodiment and FIGS. 12, 19, and 20 of the second embodiment forming part of the disclosure includes a trademark. Specifically, Intel® is a registered trademark of Intel Corporation.
